UNITED STATES PATENT OFFICE.

FRANK PERRY, OF TIPTON, ENGLAND, ASSIGNOR TO INDUSTRIAL INVENTIONS LIMITED, OF TIPTON, STAFFORD, ENGLAND.

INCANDESCENT GAS-LIGHTING.

1,312,046.

Specification of Letters Patent.

Patented Aug. 5, 1919.

Application filed January 18, 1919. Serial No. 271,799.

To all whom it may concern:

Be it known that I, FRANK PERRY, residing at 68 Dudley road, Tipton, in the county of Stafford, England, a subject of the King of Great Britain and Ireland, have invented 5 certain new and useful Improvements Relating to Incandescent Gas-Lighting, of which the following is a specification.

This invention relates to incandescent gas lighting, and has for its object to construct 10 improved inexpensive means whereby a small light can be obtained.

In the accompanying sheet of explanatory drawings:

15 Figure 1 is a perspective view showing the front and Fig. 2 a like view showing the rear of an illuminating device constructed in accordance with this invention.

In carrying the invention into effect as 20 shown a burner *a* fitted with a steatite tip and having a small orifice is used, the burner delivering only a small quantity of gas at full pressure. The burner is one of very small size giving a bat's-wing, rat-tail 25 or other like flame. For example a burner consuming one-third to one-half a cubic foot of coal gas per hour is sufficient. When supplied with gas at full ordinary town pressure such a burner gives a non-luminous flame without previous admixture with air. At a convenient distance in front of the burner, which is preferably arranged 30 horizontally, is secured a flat or other piece of refractory mesh *b* of similar material to that used in the usual cylindrical mantles, the plane of the refractory mesh being preferably at right angles to the axis of the

burner. This refractory material may be rectangular or circular in shape and is preferably flat or nearly flat. The refractory 40 material is carried on a metal frame *c* constructed from thin sheet or strip and having its edges turned over to grip the edges of the refractory material. Integrally with the frame is a connecting stem *d* having one 45 end shaped to form a slotted cylindrical gripping piece *e* which can fit over and grip the cylindrical body of the burner. The burner flame impinges on the back of the refractory material and raises the same to 50 incandescence.

An illuminating device as above described is capable of giving sufficient light for many domestic and other purposes. Also it can readily be fitted to any standard gas fitting 55 which will take an ordinary bat's-wing or like burner.

Having thus described my invention what I claim as new and desire to secure by Letters Patent is:—

An illuminating device comprising in combination a small gas burner from which the gas issues without previous admixture of air, a flat piece of refractory mesh, a light sheet metal frame having its edges 65 bent over to grip the mesh, a stem formed integral with the frame, and a slotted cylindrical gripping piece formed with the stem and adapted to grip the body of the burner, substantially as described.

In testimony whereof I have signed my name to this specification.

FRANK PERRY.
